Primary Examiner — Katherine Glennon(74) *Attorney, Agent, or Firm* — Schwegman Lundberg & Woessner, P.A.(57) **CLAIM**

The ornamental design for a dual display computer with a keyboard, as shown and described.

DESCRIPTION

FIG. 1 is a front view of a dual display computer with a keyboard, showing our new design, according to a first embodiment, with the keyboard shown in an operating configuration;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a bottom-front-left perspective view thereof;

FIG. 8 is a bottom-front-right perspective view thereof;

FIG. 9 is a top-front-left perspective view thereof;

FIG. 10 is a top-front-right perspective view thereof;

FIG. 11 is a top-rear-left perspective view thereof; and,

FIG. 12 is a bottom-rear-left perspective view thereof.

The broken line showings of a logo (e.g., “intel”) are for the purpose of illustrating environmental structure, and the broken lines form no part of the claimed design.

The shade lines show surface contour and not surface ornamentation.
